DESIGN FOR A STOVE.

SPECIFICATION forming part of Design No. 13,899, dated May 15, 1883.

Application filed September 28, 1882. Term of patent 14 years.

UNITED STATES PATENT OFFICE.

GEORGE O. BERGSTROM, OF NEENAH, WISCONSIN, ASSIGNOR TO BERGSTROM
BROTHERS & CO., OF SAME PLACE.

DESIGN FOR A STOVE.

SPECIFICATION forming part of Design No. 13,899, dated May 15, 1883.

Application filed September 28, 1882. Term of patent 14 years.

To all whom it may concern:

Be it known that I, GEORGE O. BERGSTROM, a citizen of the United States, residing at Neenah, in the county of Winnebago and State 5 of Wisconsin, have invented and produced a certain new and original Design for Stoves, of which the following is a specification, reference being had to the accompanying drawings, and to letters or figures of reference marked 10 thereon, which form a part of this specification.

The accompanying cut represents a perspective view of my newly-designed stove.

The leading features of my design relate to the ornamental raised and incised figures 15 formed on the doors of the oven, closet, and fire-box, in the shape of the front doors and the windows in the same, and the ornamental incised figures above and between said windows, and to the ornamental incised figures on the 20 legs.

The oven-doors A, closet-doors B, panels C, and fuel-box door D have smooth rounded surfaces, upon which there is no dividing-line within which the ornamental figures are confined; but instead they are gradually curved from the plane of their centers to their marginal edges, while the ornamental figures thereon extend across the even part of their surfaces and over the rounded edges to or near 25 their margins. The oven-doors A are provided with ornamental raised and incised figures a b and panel d. The door of the fuel-box D and the panel C are provided with ornamental figures F and bars K. The closet-doors B are 30

provided with ornamental figures G. The 35 front doors, L, are provided with windows H H H, rectangular in shape, above and between which are ornamental raised and incised figures I. The door J is provided with ornamental incised figures M, and the legs N are 40 ornamented with marginal lines and incised figures O and P. The base R of the front door curves forward and downward from the windows H to its lower edge, as shown.

Having thus described my design, what I 45 claim as new, and desire to secure by Letters Patent, is—

1. The ornamental incised and raised figures a and b and panel d on the oven-door A.
2. The ornamental raised and incised figures 50 F and K on panel C.
3. The ornamental raised and incised figures G on door B.
4. The front door, L, having rectangular windows H and curved base R, said base curving downward and forward from said windows, 55 said windows being provided with ornamental borders I, as shown.
5. The ornamental incised figure M on door J.
6. The ornamental incised and raised figures 60 O and P on legs N.

In testimony whereof I affix my signature in presence of two witnesses.

GEORGE O. BERGSTROM.

Witnesses:

JOHN SHIELLS,
ALEX. MCNAUGHTON.
